UNITED STATES PATENT OFFICE.

SAMSON D. WRIGHT, OF CLEVELAND HEIGHTS, OHIO.

DUMP CAR.

Application filed October 5, 1922. Serial No. 592,616.

This invention relates to improvements in dump cars used for transporting ore, coal and like materials, the present invention relating more especially to dump cars having 5 the hopper bottom.

The objects of this invention considered generally are to provide an improved mechanism for operating the bottom doors of a dump car, such as shown in my Patent No. 1,307,428 of June 24, 1919, to which reference 10 may be had for a fuller understanding of the present invention.

More particularly, it is the object of the present invention to provide means for preventing accumulation of materials, such as ore and the like, upon the tracks of the door rollers; to provide means for closing the openings through which extend the shafts of the door rollers; and to provide sealing 20 plates upon the roller shafts for rotatable movement therewith so as to maintain the openings closed against materials in the car finding their way onto the roller tracks.

Another object of this invention is to provide means for automatically breaking the drive connection of the door opening mechanism when there is an obstruction to the closing of the doors; more particularly to provide a slip clutch connection in the door 30 operating shaft so as to prevent transmission of power to the doors whenever the gates become caught.

Another object consists in providing a fluid motor means for operating the doors 35 which is so arranged as to afford a cushioning action for the piston of the fluid motor; furthermore to provide adjustable valves for the fluid motor so as to regulate the degree of cushioning effect upon the piston.

Other objects of this invention will appear from the following description and claims when considered in connection with the accompanying drawings.

Fig. 1 is a side elevation of one end portion of the car, parts being broken and in section; Fig. 2 is partly an end elevation and partly in section on line 2—2 of Fig. 1, the doors being closed; Fig. 3 is a detail view of one of the panels and parts associated therewith; Fig. 4 is a view similar to Fig. 2 and shows the doors open; Figs. 5 and 6 are views similar to Figs. 4 and 2, respectively, but taken from the inside of the car; Figs. 7 and 8 are detail views of a sealing plate; Fig. 9 is an enlarged view of a part of Fig. 1; Figs. 10 and 11 are detail views of the

slip clutch connection; Fig. 12 is a view similar to Fig. 1 but showing a modified form in which a cushioning means is provided; Figs. 13 and 14 are detail views of the air 60 cushioning device; and Fig. 15 is a view similar to Fig. 6 but showing the modified arrangement.

The dump car, which is of the same general type as that shown in my patent above 65 referred to, comprises inclined end walls 1 and side walls 2, which have their lower portions also inclined as indicated at 3, the inclined side and end wall portions terminating at side sills 4. The bottom part of 70 the hopper of the dump car consists of panels 5, those panels forming the end walls being provided with openings 6 of the particular form illustrated in the drawings for a particular purpose to be later explained. 75 Suitable channel bars and I-beams are provided for bracing the wall members of the car as well as suitable means for securing the same in the arrangement here illustrated. The car is provided with the usual 80 truck 7 with wheels 8. A housing indicated in a general way by reference numeral 9 is provided at each end of the bottom part of the hopper for the purpose of enclosing certain parts of the door operating mechanism. Near the bottom of inclined portions 3 of the side walls are pivoted links 10 which have their other ends pivoted at 85 points 11 to the upper ends of doors 12. As clearly indicated in the drawings, these 90 doors when closed are inclined toward the middle of the car and are adapted to be opened by moving their lower ends in a substantially horizontal plane. Suitably mounted upon the lower end portions of 95 the doors are rollers 13 which have extensions 13^a pivotally connected with links 14 and 14^a which in turn are pivotally connected to crank arms 15 and 15^a respectively mounted upon shaft 16. This shaft is suitably supported in bracket 17 fixed to the car 100 frame and has fixed thereon crank arm 18 which in turn has pivotal connection with connecting link 19. Link 19 is pivoted to crank arm 20 fixed upon shaft 21, which in turn has fixed thereon crank arm 22. Crank 105 arm 22 is pivotally connected with arm 23 which has pivotal connection for operation thereby with main crank shaft 24. Shaft 24 is operated through a suitable gear combination indicated in a general way by reference numeral 25, which in turn is operated 110

by main drive shaft 26. Shaft 26 has mounted thereon pinion 27 which meshes with gear 28 forming part of a slip clutch connection leading from reversible electric motor 29. The motor and other parts are supported upon a suitable extension from the side sills at the end of the car. Gear 28 is adapted to be clutched by frictional engagement between friction plates 30 of bronze, fiber, or other suitable material which engage upon their other faces with members 31 and 32.

Member 31 is fixedly mounted upon main operating shaft 26 of the motor, while member 32 is keyed upon shaft 26 for lengthwise movement thereon. Spring tension is provided between members 31 and 32 by means of rods 34 which extend therethrough and one end portion of each rod is surrounded by spring 35 bearing against member 32 and washer retained by a nut 36.

Duplicate rollers 13 are provided at the two ends of the dump car hopper and are adapted to roll upon tracks 37 suitably secured upon the floor of housing 9. Shafts 13^a of the rollers are adapted to move along the upper edges of openings 6 which determine the limits of movement of the rollers while the inclined edges 6^a of openings 6 prevent deposit of materials thereupon. The outer end portions of tracks 37 are curved upwardly as clearly indicated in the drawings, so as to also serve as a means of limiting the rolling movement of the rollers.

Spacing blocks 38 are suitably secured at spaced intervals to the outer face of panels 5 and have secured on the outer faces thereof channel bars 39 so as to provide slots between the spacing members for a purpose to be later explained. Plates 40 form a floor for housing 9 which has outer wall members 41. The side walls of housing 9 are, however, cut out as indicated at 42 to accommodate the movement of crank arm 18 therethrough.

As a means of preventing accumulation of ore or other materials upon tracks 37, I have provided the sealing plates 43 upon the two ends of the shafts 13^a, these sealing plates being of the particular form illustrated in the drawings and being so situated as to have movement in the open ways between the spacing members 38. In other words, sealing plates 43 are located outside of panel members 5 between openings 6 and tracks 37 so as to protect the tracks against the deposit and accumulation of materials thereupon, thereby preventing any such hindrance to the operation of the rollers upon their tracks. Sealing plates 43 which are fixed upon shafts 13^a have a rotary movement therewith, and are provided with teeth 43^a for the purpose of cutting through any material which might accidentally become lodged in the spaces between spacing blocks 38, such material then falling through these

spaces. Suitably mounted upon the outer face of wall panels 5 are pins 43^b which cooperate with slots 43^c provided in sealing plates 43, so as to constitute a means of defining the movement of the sealing plates. Thus it will be seen upon reference to the drawings that during the opening and closing movements of the doors as well as when the doors are standing either open or closed, sealing plates 43 entirely cover openings 6, so as to prevent escape of any of the materials from the car hopper to the tracks of the rollers.

According to the modified form of my improved device, shaft 16 is provided with pinion 44 which is adapted to be actuated by rack 45 meshing therewith. Rack 45 is connected with and driven by piston rod 46 of piston 47 which constitutes part of a fluid motor. This motor is suitably mounted on the car frame and a particular combination and arrangement of air supply and discharge connections are provided so as to afford a cushioning effect for the piston as it nears the end of its stroke in either direction. This will be clear from Figs. 13 and 14 in which the air or other fluid is supplied to or discharged from one side of the piston through pipe 48 and butterfly valve 49 is provided in branch supply pipe 50. On the other side of the piston there is provided pipe 51 through which air may be supplied or discharged, and a similar butterfly valve 52 is provided in branch supply pipe 53 so as to afford connection with the other side of the piston. Upon air being supplied through pipe 48 so as to force the piston to the right, as viewed in Figs. 13 and 14, check valve 52 will be closed so as to prevent discharge of air therethrough. In order to control the discharge of air from the right side of the piston, I have provided branch pipe 54 connecting the right-hand side of the piston with pipe 51, and in this pipe 54 there is provided valve 55 which can be set as desired so as to control the rate of discharge of air from the cylinder as the piston moves toward the right, as viewed in Fig. 13. Thus, as the piston moves in this direction, the air instead of being freely discharged will be discharged more or less slowly so as to effect a cushioning action for the piston as it approaches its end of travel, thereby easing up the action of the piston and preventing any pounding of the same against the end of the cylinder. Then upon changing the path of the air supply and discharge in the well known manner so as to force the piston toward the left, air is supplied to the cylinder through valve 52 and is prevented from escaping through valve 49, but is more or less gradually permitted to escape through valve 56 which, like valve 55, can be set in the position desired so as to create a cushioning effect for the piston. The connections

between shaft 16 and the doors for opening and closing the same are otherwise the same in this modified form as in the first form above described.

5. What I claim is:—

1. A dump car comprising a hopper body, doors for closing the bottom opening of said hopper, rollers connected to said doors, horizontally extending tracks for said rollers, means for operating said doors, and automatically movable means free of connection to said doors for preventing deposit of the contents of the car upon said tracks at all times.
15. 2. A dump car comprising a hopper body, doors for closing the bottom opening of said hopper, rollers connected to said doors, horizontally extending tracks for said rollers, means for operating said doors, and automatically movable means free of connection to said doors for preventing deposit of the contents of the car upon said tracks.
25. 3. A dump car, comprising a hopper body, doors for closing the bottom opening of said hopper, rollers connected to said doors, horizontally extending tracks for said rollers, means for operating said doors, and means movable with the doors as the same are opened or closed but free of connection thereto for preventing deposit of the contents of the car upon said tracks.
35. 4. A dump car comprising a hopper body, doors for closing the bottom opening of said hopper, rollers connected to said doors, horizontally extending tracks for said rollers, means for operating said doors, and rotatable seal plates having operative connection with said rollers for preventing deposit of the contents of the car upon said tracks.
40. 5. A dump car comprising a hopper body, doors for closing the bottom opening of said hopper, roller shafts extending through openings in the walls of said body, rollers on said shafts and connected to said doors, horizontally extending tracks for said rollers, means for operating said doors, and seal plates for said body openings, whereby the contents of the car are prevented from collecting upon said tracks.
50. 6. A dump car comprising a hopper body, doors for closing the bottom opening of said hopper, roller shafts extending through the walls of said body, rollers on said shafts and connected to said doors, horizontally extending tracks for said rollers, means for operating said doors, and seal plates having movement corresponding to the movements of said doors for preventing deposit of the contents of the car upon said tracks.
60. 7. A dump car comprising a hopper body, doors for closing the bottom opening of said hopper, roller shafts extending through the walls of said body, rollers on said shafts and connected to said doors, horizontally extending tracks for said rollers, means for operat-

ing said doors, and seal plates mounted upon said roller shafts between the walls of the hopper and said tracks and adapted for movement with said doors, whereby the contents of the car are prevented from collecting upon said tracks.

8. A dump car comprising a hopper body, doors for closing the bottom opening of said hopper, roller shafts extending through the walls of said body, rollers on said shafts and connected to said doors, horizontally extending tracks for said rollers, means for operating said doors, and seal plates having cutting edge portions mounted upon said roller shafts between the walls of the hopper and said tracks and adapted for movement with said doors, whereby the contents of the car are prevented from collecting upon said tracks.

9. A dump car comprising a hopper body, doors for closing the bottom opening of said hopper, opposite walls of said body having elongated openings, rollers on said shafts and connected to said doors, horizontally extending tracks for said rollers, means for operating said doors, and means free of connection to said doors for maintaining said elongated openings closed during the operation of said doors, whereby the contents of the car are prevented from collecting upon said tracks.

10. A dump car comprising a hopper body, doors for closing the bottom opening of said hopper, rollers connected to said doors, horizontally extending tracks for said rollers, and door operating means including a fluid actuated piston, said operating means being provided with adjustable means for cushioning the piston.

11. A dump car comprising a hopper body, doors for closing the bottom opening of said hopper, rollers connected to said doors, horizontally extending tracks for said rollers, and door operating means including a fluid actuated piston, said operating means being provided with adjustable means for cushioning the piston upon both sides thereof.

12. A dump car, comprising a hopper body provided with a bottom opening, a door for closing said bottom opening, a roller connected to said door, a substantially horizontally extending track for said roller, means for operating said door, and means having operative connection with said roller for preventing deposit of the contents of the car upon said track.

13. A dump car, comprising a hopper body provided with a bottom opening, a door for closing said bottom opening; a roller connected to said door, a substantially horizontally extending track for said roller, means for operating said door, and rotatable means having operative connection with said roller for preventing deposit of the contents of the car upon said track.

14. A dump car, comprising a hopper body

provided with a bottom opening, a door for closing said bottom opening, a roller connected to said door, a substantially horizontally extending track for said roller, means for operating said door, and seal plates having operative connection with said roller for preventing deposit of the contents of the car upon said track.

15. A dump car, comprising a hopper body having a bottom opening, a door for closing

said opening, a roller associated with said door, a substantially horizontally extending track for said roller, door operating means, and means having a cutting edge portion for preventing the deposit of the contents of the car upon said track.

15. In testimony whereof I hereby affix my signature.

SAMSON D. WRIGHT.
